UNITED STATES PATENT OFFICE

HERMAN SCHLACHT, OF NEW YORK, N. Y.

DESIGN FOR A WATCH HOLDER

Application filed November 5, 1929. Serial No. 33,345. Term of patent 7 years.

To all whom it may concern:

Be it known that I, HERMAN SCHLACHT, a citizen of the United States, residing at New York city, in the county of New York and State of New York, have invented a new, original, and ornamental Design for a Watch Holder, of which the following is a specification, reference being had to the accompanying drawing, forming part thereof, in which—

Fig. 1 is a perspective view of a watch holder showing my new design, in an open position; and

Fig. 2 is a perspective view showing the same in a closed position.

I claim:

The ornamental design for a watch holder, as shown.

HERMAN SCHLACHT.
